UNITED STATES PATENT OFFICE.

FRANK S. JAMES, OF GRASS VALLEY, CALIFORNIA.

ROD-EXTRACTOR.

1,107,955.

Specification of Letters Patent. Patented Aug. 18, 1914.

Application filed September 19, 1913. Serial No. 790,807.

To all whom it may concern:

Be it known that I, FRANK S. JAMES, a citizen of the United States of America, residing at Grass Valley, in the county of 5 Nevada and State of California, have invented new and useful Improvements in Rod-Extractors, of which the following is a specification.

This invention relates to improvements in 10 rod extractors and has particular application to a device of this class whereby rods, drills and other like tools may be extracted or withdrawn from the ground in the event of the same becoming stuck.

15 In carrying out the present invention it is my purpose to provide a device of the character described which will embody among other features a frame having a fulcrum point at one end and a handle at the 20 opposite end, a gripping block pivoted within the frame and adapted to grip the rod and maintaining the same plane in the swinging movement of the frame about the fulcrum point whereby the gripping block will 25 be elevated and the rod withdrawn in the movement of the frame.

It is also my purpose to provide a rod extractor which will express the desired features of simplicity, efficiency and durability, 30 one which may be manufactured and marketed at a minimum expense.

With the above recited and other objects in view the invention consists in the construction, combination and arrangement of 35 parts hereinafter set forth in and falling within the scope of the claim.

In the accompanying drawing: Figure 1 is a top plan view of a rod extractor constructed in accordance with my invention. 40 Fig. 2 is a longitudinal sectional view therethrough. Fig. 3 is a transverse sectional view of the same. Fig. 4 is a view in side elevation showing the rod extractor in use.

Referring now to the accompanying drawing in detail the numeral 1 designates a frame constructed of any suitable material and preferably oblong in outline. Secured to one end of the frame and depending therefrom is a fulcrum block 2 while connected 45 with the opposite end of the frame and extending outwardly and upwardly therefrom is a handle 3 by means of which the frame 50 may be swung about the fulcrum block.

The numeral 4 designates a gripping block which, in this instance, conforms to the 55 shape of the frame 1 and fits within the latter. This block is relatively short as compared with the length of the frame and is formed with an elongated slot 5 merging into an irregular opening 6 at one end thereof, such opening being designed to receive 60 the rod to be extracted. This gripping block 4 is pivoted within the frame 1 by means of a pin 7 passed through the frame and the block and the opposite ends of the gripping 65 block are spaced apart equal distances from the ends of the frame 1 and 6 mounted for swinging movement upon the pin 7 within the slot 5 in the gripping block is a jaw 8 having one end toothed as at 9 and designed 70 to move into the opening 6.

In the use of the device the jaw 8 is swung to open position, that is, the toothed end thereof is moved out of the opening 6, and the block 4 slipped over the end of the rod 75 to be extracted, the rod being passed through the opening 6. After the block is placed upon the rod the jaw 8 is swung to closed position so that the toothed end thereof bites against the adjacent portion of the rod. In 80 this position of the parts the fulcrum block 2 rests upon the ground while the handle 3 is within a convenient reach of the operator, the fulcrum block and frame resting in a horizontal plane. As pressure is applied to 85 the handle to swing the frame about the fulcrum block, the gripping block maintains a horizontal position and moves in an upward direction thereby carrying the rod upwardly, as clearly illustrated in Fig. 4. 90

While I have shown and described one particular form of my invention by way of illustration, I wish it to be understood that I do not confine myself to the precise details of construction herein described and delineated, as modification and variation may be made within the scope of the appended claim. 95

I claim:

A rod extractor comprising a frame having a fulcrum block at one end thereof and a handle at the opposite end, a gripping block within said frame and capable of swinging movement therein and formed with an elongated slot and an irregular opening 100 communicating with the slot at one end, a 105

jaw within the slot in said gripping block and capable of swinging movement therein and having one end toothed and disposed adjacent to said irregular opening, and a pivot 5 pin passed through said fulcrum block and jaw and holding the parts pivotally connected.

In testimony whereof I affix my signature in presence of two witnesses.

FRANK S. JAMES.
